Abner Whitney Albany N.Y. State

Lettins Patent

in Schedule referred to in this Letter Patent and making part of the same containing a description in the words of the said Abner Whitney himself of his improvement in the Spark Extinguisher and Heat condenser with Whitney having assigned all his rights title and interest in and to the equal half of this Patent to Give P. Bunn.

To all to whom these presents shall come. We the known that I Abner Whitney of the City and County of Albany and State of New York have invented a new and useful spark extinguisher and heat condenser and that the following is a full and exact description thereof. The Spark extinguisher and heat condenser are made of any proper material which will withstand fire in the form of a cylinder so as may any dictate (see No 1 in Diagram A.) from and substantial at the bottom with an aperture in the middle to receive the pipe of the furnace below (No 2 & 4.) at the top (No 3.) it is made cylindrical and is formed something in fashion of a common funnel) that it may enter if required a tube a pipe of the same dimensions as that placed upon it proceeding from the furnace (No 4.) immediately below the shoulder (No 3. when the pipe begins to turn) two iron bars No 5. which pass from side to side and off each other at right angles in the center (No 5. horizontal) these bars are placed upon a plate of iron called a damper (No 6.) which must be fastened to the furnace and pass the barrel of the barrel over in proportion to the surfaces of the pipe of the furnace which must always regulate the bore of the cylinder. That is if the pipe before enters 10 in diameter the cylinder ought to be about the proportion of thirty inches 30 in diameter that is about 3 to 1. and according to about that proportion if the pipe is larger or smaller. The Damper (No 6.) placed at the top as above mentioned would agreeable to this proportion appear to be about 26 inches in diameter which will be about

In stroke 2. remove the cylinder through which the smoke will come - and it is recommended to have the outer cylinder a little smaller in diameter, than this will be more convenient for purposes - Within this cylinder is placed another cylinder (No. 7-6) of about the same size of the cylinder above described, constructed in the same manner and form as, the outer cylinder but made without any bottom. The top, however, to be made of the same height, as the pipe of the furnace and though for most purposes, the cylinder may be made stationary, yet in cases where the draft of the furnace shall require it to be inclined, it is advised to be made to turn down according to the law of the lever by means of slides (No. 8) as herein after mentioned. This cylinder No. 7, will come down so far as to cover the pipe of the furnace without the outer cylinder but leaving a space equal to the bottom of the cylinder large enough for the operation of the air, and shall partly of sediment as may chance to collect. This cylinder is suspended within the other, by means of croft bars, of iron passing through both cylinders on a hole, is also fixed a stampor in the same manner as above described and around the framework of this stampor, an opening within this cylinder which, on contraction, will expand the cylinder to fit the pipe of the furnace (see a figure more) are bars No. 5, which ought past this inner cylinder and by which this stampor is suspended will be caused to pass through both cylinders from side to side, and are fastened on the outside of the outer cylinder by nut screws on the ends of 10 ft. and on the inside between the two cylinders ought be placed thumbles (d) to keep the inner cylinder in its proper position, and further to support and suspend the inner cylinder. There ought to be two other screws with heads (c) passing from the inside of the inner cylinder through the outer cylinder, but also with nut screws (9) upon the outside one above and the other below each end of the bars, also mentioned. on these also ought to be placed thumbles (d) to aid in keeping the inner cylinder in its position because it will be found that the inner machinery will be heated to nearly melting and will become disordered without this properly braced.

Damper to the shoulder No 3 nine inches (9). No 3, from the decomposition of matter within the cylinder when there will collect an oxydated sub-stance in small particles called ash, this will fall upon the bottom of the cylinder and may be removed by a small door (h) upon each side of the cylinder at the bottom of which may be opened at pleasure when this invention is used in open air, but otherwise if used in water. If the operator wishes further to condense heat he may do so that he can do it by adding one or more dampers to the inside of the cylinder and also add flanges appended from the cylinder above the dampers. But in all cases where he introduces a flange or object that may bear any other name he must take care to provide the throat or apertures for the smoke to pass freely. It must not be understood that the cylindrical shape is supposed to be the only form in which this invention may be made, any other form that fancy may dictate will be of equal utility, if the construction will pay attention to the first proportions of the parts, that the shape of the cylinder and the cylindrical mouth may be conformed to the cylinder. What I claim is, among other inventions and not previously known is the above described, sometime is the invention construction of partitioning and separating the whole machine or improvement, as is above described for the ring and baffle represented in the said above specifications and to be applied to the pipe of some thing to prevent the escape of sparks of fire, and to condense and create heat. Also to the pipe of a Locomotive car or engine and to steam boats, for the prevention of sparks, also if placed near a furnace, where the melting of iron or something requires except of heat this invention will be found highly useful.

To witness that the above is a true specification of my said improvement as above described. I have hereunto set my hand this day of February 1836.
